H. P. HOYLE

CENTRIFUGAL SEPARATOR

Filed July 12, 1923

UNITED STATES PATENT OFFICE.

HENRY PATRICK HOYLE, OF DURHAM, ENGLAND.

CENTRIFUGAL SEPARATOR.

Application filed July 12, 1923. Serial No. 651,086.

To all whom it may concern:

Be it known that I, HENRY PATRICK HOYLE, a subject of the King of Great Britain, residing at 46 North Bailey, Durham, England, have invented new and useful Improvements in Centrifugal Separators, of which the following is a specification.

This invention relates principally to apparatus for separating solids from liquids, but such apparatus may be used for separating liquids of different specific gravity from one another.

According to this invention the apparatus comprises a centrifugal distributor which rotates within a rotating vessel, and means for discharging the heavier portion of the charge from the vessel which portion is driven against the sides of the rotating vessel by the action of the distributor. The rotating vessel is preferably a truncated cone and is provided with a worm driven at a different speed from the rotating vessel for discharging the material deposited upon its inner surface.

The upper part of the centrifugal distributor may be connected to a sleeve having upon it a pulley by which it is rotated, and the lower part may be connected to a shaft having upon it a pinion in gear with a double pinion which also gears with a pinion on a sleeve surrounding the shaft, which sleeve carries the conical vessel.

The worm may be mounted upon the outside of the centrifugal distributor. The material to be separated may be fed to a hopper provided with revolving agitators or means for supplying compressed air for agitating the material. The material passes from the hopper down a pipe within the sleeve connected to the upper portion of the distributor to the centrifugal distributor.

The accompanying drawing is a section of a separator made in accordance with this invention.

a is a hopper to which the material to be separated is fed, provided with agitators *b* mounted upon a sleeve *c* having a handle *d* by which it can be turned. The material is led from hopper *a* through a pipe *e* to the upper part *f* of a centrifugal distributor, the amount being regulated by means of a valve *g*. The part *f* is mounted upon a sleeve *h* having upon it a pulley *i* by which it is rotated. The lower part *j* of the distributor is connected to a shaft *k* having at its end

a pinion *l* gearing with a double pinion *m* keyed to a shaft *n* and the double pinion *m* is also in gear with a pinion *o* on a sleeve *p* surrounding the lower part of the shaft *k* and carrying a conical vessel *q*. A worm *r* is fixed to the outside of the centrifugal distributor and to a boss *s* mounted on the shaft *k*. The bottom of the conical vessel is closed by a base plate *t* having outlets *u* for material of less specific gravity, whence the material passes to an outlet *v* in the base plate *w*. The heavier material is discharged by the worm *r* over the top of the conical vessel *q* where it falls into a chute *x*. The shaft *k* is provided with thrust disks *A* and *B* whilst between the sleeve *p* and the plate *w* are ball bearings *C*. On the end of the shaft *n* is a centrifugal oil pump *D* which forces the oil from an oil well *E* through a pipe *F* to the shaft *k*. The conical vessel *q* is contained in a casing *G* mounted upon a frame *H* and supports a frame *J* in which are ball bearings *K* on which the sleeve *h* turns, the frame *J* also carrying the hopper *a*.

It will be seen that in the centrifugal separator described the thrust on the worm *r* is balanced by an equal thrust on the vessel *q* in the opposite direction.

Attention is called to the fact that the feed supply is central to the distributor for which reason the balance of the apparatus is maintained, and also the distributor has a suction effect which will suck in feed, even if the hopper *a* is located at a lower level than the exit openings of the distributor.

What I claim is:—

1. A centrifugal separator comprising a centrifugal distributor, a feed for the centrifugal distributor central to the separator, a vertical rotating vessel mounted outside the centrifugal distributor, the mouth of the centrifugal distributor being located in the upper part of the rotating vessel, means for discharging the heavier portion of the charge from the top of the vessel and means for rotating the distributor and the vessel at different speeds.

2. A centrifugal separator comprising a centrifugal distributor, a feed for the centrifugal distributor central to the separator, a rotating vessel mounted outside the centrifugal distributor and having its smaller end at top, the mouth of the centrifugal distributor being located in the upper part

- thereof, a discharging worm inside the vessel, and means for rotating the distributor and the vessel at different speeds.
3. A centrifugal separator comprising a centrifugal distributor, a feed for the centrifugal distributor central to the separator, a conical rotating vessel mounted outside the centrifugal distributor, the mouth of the centrifugal distributor being located in the upper part thereof, means for discharging the heavier portion of the charge from the top of the vessel and means for rotating the distributor and vessel at different speeds.
4. A centrifugal separator comprising a centrifugal distributor, a feed for the centrifugal distributor central to the separator, a conical rotating vessel having its smaller end at the top and mounted outside the centrifugal distributor, the mouth of the centrifugal distributor being located in the upper part thereof, a discharging worm inside the vessel, and means for rotating the distributor and the vessel at different speeds.
5. A centrifugal separator comprising a centrifugal distributor consisting of an upper and a lower part connected together, a sleeve carrying the upper part, a shaft carrying the lower part, a rotating vessel mounted outside the centrifugal distributor, a second sleeve on the shaft and carrying the vessel, a double pinion, a pinion on the shaft gearing with the double pinion, a second pinion on the second sleeve gearing with the double pinion, means for discharging the heavier portion of the charge from the vessel, and means for rotating the first sleeve.
6. A centrifugal separator comprising a centrifugal distributor consisting of an upper and a lower part connected together, a sleeve carrying the upper part, a shaft carrying the lower part, a rotating vessel mounted outside the centrifugal distributor, a second sleeve on the shaft and carrying the vessel, a double pinion, a pinion on the shaft gearing with the double pinion, a second pinion on the second sleeve gearing with the double pinion, a discharging worm inside the vessel and adapted to be rotated at a different speed from the vessel, and means for rotating the worm and the first sleeve.
7. In a centrifugal separator, the combination of a hopper, a centrifugal distributor, a pipe leading from the hopper to the distributor, a sleeve surrounding the pipe and connected to the distributor, a shaft connected to the distributor, a conical vessel, a second sleeve on the shaft and carrying the conical vessel, gearing between the second sleeve and the shaft, a worm mounted on the centrifugal distributor, and means for driving the first sleeve.
8. A centrifugal separator comprising a feed pipe central to the separator, a sleeve mounted on the feed pipe, a centrifugal suction distributor carried by the sleeve, a ro-

tating vessel mounted outside the centrifugal distributor, means for discharging the heavier portion of the charge from the vessel and means for rotating the distributor and the vessel.

9. A centrifugal separator comprising a feed pipe central to the separator, a sleeve mounted on the feed pipe, a centrifugal suction distributor carried by the sleeve, a rotating vessel mounted outside the centrifugal distributor, a discharging worm inside the vessel, and means for rotating the worm, the separator and the vessel.

10. A centrifugal separator comprising a feed pipe central to the separator, a sleeve mounted on the feed pipe, a centrifugal suction distributor carried by the sleeve, a conical rotating vessel mounted outside the centrifugal distributor, means for discharging the heavier portion of the charge from the vessel and means for rotating the distributor and the vessel.

11. A centrifugal separator comprising a feed pipe central to the separator, a sleeve mounted on the feed pipe, a centrifugal suction distributor carried by the sleeve, a conical rotating vessel mounted outside the centrifugal distributor, a discharging worm inside the vessel, and means for rotating the worm, the distributor and the vessel.

12. A centrifugal separator comprising a feed pipe central to the separator, a sleeve mounted on the feed pipe, a centrifugal suction distributor carried by the sleeve, a rotating vessel mounted outside the centrifugal distributor, a discharging worm inside the vessel and mounted on the distributor, and means for rotating the vessel and distributor at different speeds.

13. A centrifugal separator comprising a feed pipe central to the separator, a sleeve mounted on the feed pipe, a centrifugal suction distributor carried by the sleeve, a rotating vessel mounted outside the centrifugal distributor, a discharging worm inside the vessel and mounted on the distributor in equilibrium so that the thrust on the discharge worm is balanced by an equal thrust on the vessel, and means for rotating the vessel and distributor at different speeds.

14. A centrifugal separator comprising a feed pipe central to the separator, a sleeve mounted on the feed pipe, a centrifugal suction distributor carried by the sleeve, receiving the charge from the pipe and giving it a centrifugal motion, a discharging worm carried by the distributor, a rotating vessel outside the distributor, and means for rotating the vessel and distributor at different speeds.

In testimony that I claim the foregoing as my invention I have signed my name this 15th day of June, 1923.
